HENRY HEBBARD, OF NEW YORK, N. Y.

Design No. 3,315, dated January 5, 1869.

DESIGN FOR A SPOON OR FORK-HANDLE.

The Schedule referred to in these Letters Patent and making part of the same.

To all whom it may concern:

Be it known that I, HENRY HEBBARD, of the city, county, and State of New York, have invented or produced a new Design for Ornamenting the Handles of Spoons, Forks, and other articles of table-ware; and I do hereby declare that the following is a full description of the same, reference being had to the accompanying drawings, forming a part of this specification, the same letters of reference, wherever they occur, referring to like parts.

Figure 1 represents the front side of the spoon.

Figure 2 represents the back side of the spoon.

Letter *a* represents the shank of the spoon, from which projects the stem *b*, having a raised thread *c* on each edge, and up its middle a double-thread *d*, which terminate in a small bunch of grapes, *e*, at the shank or bowl of the spoon.

Surmounting the stem is the shield *f*, or head-piece of the handle, terminating at the top in a lance-point, around the edge of which is a raised thread, *g*, which extends down the face of the shield to the junction of the head-piece with the stem, where it ends in the thread, at the edges of it.

At the outside of the thread *g* is a feather-like edge, *h*, commencing at a point near the junction with the stem, and gradually increasing in width to near the head or point of the handle, till it loses itself in the scroll-like figures *i*, branching out from a bunch of fruit, *j*, on the upper edge of the shield proper, which said bunch of fruit is supported by loops *k* attached to the scroll *i*.

Between these scrolls, and resting upon the bunch of fruit *j*, is a leaf-like figure, *l*, which nearly covers the face of the lance, the ground-work of which, as well as down around the central shield, is corrugated.

At the junction of the stem with the shield-piece, the threads *c* terminate on the face of the shield-piece in a feather, *m*, just underneath the shield-piece proper,

from the lower point of which projects a double-raised thread *n*, having a rosebud entwined with them, and all bound together by a ribbon *p*, to unite the whole with the upper end of the double-raised thread *d* of the stem, to complete the design for the front side of the spoon.

On the back side of the spoon the heel is covered with a bunch of grapes, *q*, between two leaves, the stems of all of which unite in a point projecting up the middle of the stem of the spoon.

On each edge of the stem of the spoon, and up the face of the shield, are raised threads *r*, which unite at the end of the handle to form the lancet-shaped point of it.

At the outside of this raised thread, and at the sides of the shield, are feather-edge-like devices *s*, which commence in a small point near the junction of the shield to the stem, and gradually increase in width till they lose themselves in two raised scroll-like figures *t*, having thin stems joined together in the middle of the shield by a ribbon, *u*, having its ends looped and spread out so as to cover the upper portion of the shield.

Between the scrolls, and covering the face of the lancet-shaped end of the handle, is a shell, *v*, which completes the devices for ornamenting the back side of the handle of the spoon.

Having now described my new design for ornamenting the handle of spoons, &c., I will proceed to set forth, what I claim, and desire to secure by Letters Patent of the United States.

I claim the design, hereinbefore described, for the handles of spoons, forks, and other articles of table-ware.

H. HEBBARD.
